UNITED STATES PATENT OFFICE

JAMES R. HUGHES, OF SOUTH BEND, INDIANA, ASSIGNOR TO THE STUDEBAKER CORPORATION, OF SOUTH BEND, INDIANA, A CORPORATION OF NEW JERSEY

TRUNK RACK

Application filed January 14, 1929. Serial No. 332,478.

This invention relates to a trunk rack or luggage carrier, and particularly to a trunk rack having a jointed trunk supporting member comprising two sections adapted to be 5 folded when not in use and unfolded and extended to a horizontal position to support a trunk or package thereon.

The principal object of the invention is to provide brackets secured to the vehicle frame 10 side members on which is pivotally mounted a jointed trunk supporting member, spring means being provided for maintaining the jointed member in folded position or securing it in extended position.

15 A further object is to provide slots in the supporting members adapted to slidably receive studs secured to one section of the jointed member whereby the jointed member is guided to folded and unfolded positions, 20 spring means also being provided for maintaining the jointed member in the respective positions.

The above being among the objects of the present invention, other objects will appear 25 which will relate to certain novel features of construction and combination of parts to be hereinafter described with reference to the accompanying drawings, and then claimed.

In the accompanying drawings which show 30 a suitable embodiment of the present invention and in which like numerals refer to like parts throughout the several different views,

Figure I is a sectional view showing the 35 jointed supporting member in partially folded position, and also in dotted lines, showing the same in folded position, the same being taken on the same section line as Figure II.

Figure II is a sectional view taken on the 40 line 2-2 of Figure IV, showing the jointed member in extended position.

Figure III is an enlarged sectional view taken on the line 3-3 of Figure II.

Figure IV is a top plan view showing the 45 jointed member in extended or trunk receiving position.

Referring to the drawings, the side frame members 10 are each provided at one end thereof with a spring or shackle receiving member 11 which is formed with a flat face

12 adapted to receive and support the downwardly extending arms 13 of supporting brackets 14. The brackets 14 are supported on the frame side members 10 forwardly of the rear ends thereof by means of the bolts 55 15, and the arms 13 are secured to the flat faces 12 of the spring receiving members 11 by the bolts 16.

As the brackets 14 which are secured to the frame members 10 are identical, special reference will be made to only one of the same, and referring particularly to Figure 1, the bracket 14 is provided with a longitudinally extending slot 17 which extends substantially the full length thereof. The slot 17 is curved 60 downwardly at its rear end at 17' for a purpose to be hereinafter described.

The trunk or baggage supporting member 18 is formed of two sections 18a and 18b united by the pivots 19 so that the sections 70 18a and 18b can be folded to the position as shown in dotted lines in Figure I or extended to the operative position shown in Figure II. The member 18a is pivoted at 20 to the bracket 14 adjacent the rear end thereof and adjacent to the curved portion 17' of the slot 17. A stud 21 secured to the free end of the member 18b by means of the nut 22 is adapted to slide in the slot 17 for guiding the sections 18a and 18b to the folded and 75 unfolded positions. A spring 23 riveted or otherwise secured at 24 to the bracket 14 contacts with the stud 21 for retaining the member 18 in extended position as is clearly shown in Figure II. A similar spring 25 riveted 80 or otherwise secured at 26 to the bracket 14, engages with the stud 21 when the sections 18a and 18b have been folded and the stud 21 has been moved into the curved portion 17' of the slot 17.

I am aware that trunk racks adapted to be folded when not in use have been heretofore used, but so far as I am aware no one has provided means for automatically retaining this member in folded and unfolded position 85 when the rack has been moved to that desired position. Instead, manually operated fastening means such as a screw and thumb nut has been used which had to be unloosened before the trunk supporting member could 90 100

be moved to either folded or unfolded positions.

In the present invention the sections 18a and 18b can be extended to the position shown in Figure II and retained in that position by the spring 23 which coacts with the stud 21 to prevent movement of the trunk rack until a pulling force is applied thereto. When it is desired to fold the sections 18a and 18b, the spring 23 will disengage with the stud 21 and these members can be moved to the position shown in dotted lines in Figure I in which folded position the trunk rack will be held against movement by means of the spring 25. Conversely when it is desired to extend the sections 18a and 18b to operative position, the spring 25 will be caused to disengage with the stud 21 and the sections can be extended as shown in Figure II.

20 In the specification and claims I have referred to my invention as a trunk rack, however it is to be understood that the invention is not to be so limited as the carrier can be used for any suitable purpose, as for example, 25 a carrier for suit cases, packages, boxes, luggage and the like.

It will be understood that the invention is susceptible of various changes and modifications all coming within the scope and spirit 30 of the invention as defined in the following claims.

What I claim is:

1. A trunk rack comprising, a supporting member secured to a vehicle side frame member, a jointed folding member pivoted to said supporting member adjacent one end thereof, spring means acting between said jointed folding member and said support for holding said jointed folding member in folded position, and spring means acting between said jointed folding member and said support for retaining said jointed folding member in extended position.

2. A trunk rack comprising, a supporting member secured at one end to the end of a vehicle frame side member and at the opposite end to the side member forwardly of its end, a jointed folding member pivoted to said supporting member adjacent one end thereof, spring means acting between said jointed folding member and said support for holding said jointed folding member in an inclined folded position, and spring means acting between said jointed folding member and said support for retaining said jointed folding member in a flat horizontal position.

3. A trunk rack comprising, a slotted supporting member secured to a vehicle frame side member, a jointed folding member pivoted to said supporting member adjacent one end thereof, a stud secured to the free end of said jointed member and adapted to be guided in said slot, spring means engaging said stud for holding said jointed folding member in folded position, and spring means engaging

said stud for retaining said jointed folding member in unfolded position.

4. A trunk rack comprising, a supporting member having a horizontal portion secured to a vehicle frame side member and a vertical portion secured to the end of said frame member, said supporting member having a slot therein extending substantially the length of the horizontal portion and terminating in a downwardly extending end, a jointed folding member having one side thereof pivoted to said supporting member adjacent the downwardly extending end of said slot, a stud secured to the free side of said jointed folding member and adapted to be guided in said slot, a spring secured to said supporting member to engage said stud when the same is moved into the downwardly extending end of said slot for holding said jointed folding member in a folded position, and a spring secured to said supporting member to engage said stud when the same is moved to the forward position in said slot for retaining said jointed folding member in extended position.

5. A trunk rack comprising, a supporting member having a horizontally extending portion and a vertical portion, each portion being secured to a vehicle frame side member, a jointed folding member having one side thereof pivoted to the horizontally extending portion of said supporting member, means attached to the free end of said jointed folding member slidable on said supporting member, means engaging said first means for holding said jointed folding member in folded position, and means engaging said first means for retaining said jointed folding member in extended position.

Signed by me at South Bend, Indiana, this 11th day of January, 1929.

JAMES R. HUGHES.
